DUNCAN MACRAE, OF EAST ORANGE, NEW JERSEY, ASSIGNOR TO WESTINGHOUSE LAMP COMPANY, A CORPORATION OF PENNSYLVANIA.

VACUUM DEVICE AND METHOD OF CLEANING UP RESIDUAL GASES THEREIN.

Application filed January 9, 1923. Serial No. 611,672.

This invention relates to vacuum devices and more particularly to evacuated electron devices and the cleaning up of residual gases therein.

5 An object of my invention is to provide a method of cleaning up residual gases in the bulbs of electron devices or the like, by forming the plate thereof of galvanized iron or other suitable material coated with zinc 10 and vaporizing the zinc thereof, whereby the residual gases in the bulb are sufficiently eliminated.

Another object of my invention is the provision of an electron device or the like with 15 a clean-up agent thereon applied as an even coating or deposit on a component part thereof, such as the plate, and adapted to be activated by heating the plate, in any desirable manner, after exhaustion of the 20 device.

A further object of my invention is the provision of radio tubes or the like in which a cheaper material than the customary molybdenum, for example, zinc-plated or 25 galvanized iron, is used for the plates thereof, the zinc or the like serving the double function of preventing rusting of the iron prior to its introduction into such devices and cleaning up residual gases in the 30 bulb upon activation thereof.

A still further object of my invention is the production of radio bulbs suitable for detector tubes or the like in which the required degree of exhaust is obtained in a 35 simple and economical manner.

Other objects and advantages of the invention will be made apparent as the description proceeds.

Various materials have been used for 40 cleaning up residual gases in evacuated electron devices such as radio bulbs, X-ray tubes and the like. In the copending application of H. C. Rentschler, Serial No. 582,261 filed August 16, 1922, vacuum devices and method 45 of exhausting the same, (W. L. 198) and assigned to the Westinghouse Lamp Company, is described a method of cleaning up residual gases in electron tubes by activating aluminum or aluminum and magnesium 50 or the like therein. The said application sets forth how the use of such clean-up agents obviates the necessity of producing a very high vacuum in the device by mechanical means, such as a vacuum pump. Such

cleaning-up agents, therefore, make it possible to exhaust the device to a moderate degree only and then produce the required high vacuum by vaporizing or activating the particular clean-up agent used.

The clean-up agents mentioned in said copending application are aluminum, magnesium, calcium and phosphorus, all of which have been used with varying degrees of success. All of such materials have heretofore been ordinarily applied as strips or small 65 pieces in a certain position on the plates of radio bulbs, when used therein, and activated by heating such plates by high-frequency induction or electron bombardment to temperatures sufficient to vaporize the material 70 used. The disadvantage of such an arrangement, is that a plate consisting of relatively expensive material, such as molybdenum, tungsten or the like, must ordinarily be employed and additional labor is involved in 75 attaching the clean-up material thereto, as by welding, pasting, clipping or the like.

According to my invention, I obviate the necessity of using expensive material, such as that mentioned, and avoid the additional 80 operation of fastening clean-up material thereto, by forming the plate directly from a composite metallic sheet, such as galvanized iron or some other relatively inexpensive material covered with another material 85 adapted to serve as a clean-up agent.

Although the preferred embodiment of my invention includes the use of galvanized iron for making the plate for a radio tube or the like, my invention is not limited to such, as it broadly comprises the employment of a plate uniformly covered or coated with a suitable clean-up agent and said plate may be of any desired material such as iron, nickel, molybdenum, tungsten or the like. Likewise, the clean-up agent may be any suitable material, such as zinc, aluminum, magnesium, calcium, an alloy or mixture of two or more of the same or the like applied to the plate as a uniform film or 100 coating by electro-plating, galvanizing or any other desired process.

My invention will better be understood by reference to the accompanying drawing, the single figure of which is a side elevation, 105 partly in section, of a radio tube embodying my invention and surrounded by a coil for inductively heating the plate thereof, and

such coil, shown in section, being diagrammatically indicated as connected to a source of high-frequency current.

The radio or electron device 1 comprises a bulb 2, a stem 3 sealed therein and a base 4. Supported on the stem 3 is an electrode or plate 5, another electrode or grid 6 and a cathode in the form of an electron-emitting filament 7. The stem, together with the aforementioned suitably-supported electrodes, form the mount of the electron device 1. Lead-in wire 8 connects the plate 5 to a suitable contact member 9 on the base. Lead-in wire 11 extends between the grid 6 and contact member 12 on the base 4.

The filament 7 is provided with leading-in wires 13 and 14, connected, respectively, to contact members 15 and 16 on the base 4. The plate 5 is preferably constructed of galvanized iron or iron electroplated with zinc, although it may consist of molybdenum, nickel, tungsten or the like, to which zinc has been applied as a clean-up agent, or any of the mentioned plate materials, uniformly coated with any suitable clean-up agent, such as zinc, aluminum, magnesium or calcium.

The grid 6 may be constructed of any suitable material, for example, one of the metals mentioned for constructing the plate. The filament 7 may be formed as an oxide-coated, platinum-iridium wire or of activated, thoriated or pure tungsten wire, or any other material suitable for electron-emission purposes. Prior to its introduction into the bulb, the plate 5, if of galvanized iron, is preferably cleaned of foreign material, such as dirt or grease, and, if of molybdenum or one of the other metals mentioned, may have applied thereto a thin sheet or foil of zinc or, by electroplating or the like, uniformly coated with a thin plating of zinc, aluminum, magnesium, calcium or an alloy or mixture of two or more of the same.

A combination of two or more of such clean-up agents may also be employed. The bulb 2 may then be cold-exhausted on an oil pump of the usual type to obtain a moderate vacuum therein, such as that ranging from 1 to 100 microns. The bulb 2 may then be tipped off and a coil 17, suitably connected to a high-frequency generator 18 or other suitable source of high-frequency current through a switch 19, may be applied there-around, as shown in the drawing.

Upon closing the switch 19, high-frequency current in the coil 17, will induce corresponding current in the plate and also in the residual gases in the bulb 2. These induced currents will heat the plate and other conducting parts of the device and cause the residual gases to glow or flash brightly, until the plate 5 becomes heated sufficiently to cause vaporization or activation of the clean-up agent 21 thereon. Let it be assumed that such clean-up agent, ac-

cording to the preferred embodiment illustrated, is zinc in the form of galvanizing or electroplating on an iron plate 5. An advantage obtained by this preferred arrangement is cheapness, as it is well known that galvanized iron is much cheaper than molybdenum or other conventional plate materials.

The zinc on the surface of the iron not only serves to prevent rusting of the same prior to its introduction into the electron device but it also protects the surface of the iron from occluding atmospheric gases and the like, for, as is well known, iron is galvanized by being dipped into molten zinc. Such a process heats the iron to a temperature sufficient to drive off a large proportion of occluded gases and the film of the zinc, deposited on the surface thereof, substantially prevents occlusion of additional gas, after the galvanizing process has been completed.

Some of the advantages of my invention may however be secured by using iron, electroplated with zinc, magnesium or the like, for, in that way, the iron is prevented from rusting prior to use, and the amount of the clean-up agent may be conveniently controlled by variation of the time or the plating current during the process of electroplating. In its broader aspect, my invention also contemplates the use of zinc as a clean-up material or a material or getter to improve the operation of an electron device and may be applied in any manner; for example, it may be applied as a cl.p or strip on the plate 5 in the same manner in which the aluminum clean-up agent was applied according to the copending application of Rentschler aforementioned.

When the temperature of the plate 5 has risen sufficiently, the zinc or other clean-up agent thereon melts, vaporizes and satisfactorily cleans-up the residual gases in the bulb, as well as those driven off from the plate. Any other suitable method of heating the plate 5 may be used instead of the inductive heating heretofore described, for example, the filament 7 may be heated to an electron-emitting temperature by passing an electric current therethrough, and the plate 5, heated by electron bombardment by impressing a high potential between said heated filament and the plate. If zinc is used as the clean-up material, a mirror of the same will be formed on the bulb, but it will be found that such mirror may be so restricted as not to cover the bulb to such an extent as to interfere with the proper observation in the interior thereof.

Comparative tests to determine the relative efficiency of zinc and magnesium as clean-up agents indicate that zinc apparently does not remove the residual gases as completely as magnesium, but the remaining gases do not seem to harm the electron-

emission of the filament as much as those tubes or any other evacuated devices and that remaining after a magnesium clean up. After the construction of the radio tubes and the 30
5 longer seasoning for 3½ hours at 7.7 volts, the proportion of the zinc or other clean-up agent plate current for five electron tubes with thorium activated filaments and magnesium, 35
10 gave, when tested, an average of 15 milliamperes and a range of from 6 to 27 milliamperes, while for the four zinc tubes tested, under identical conditions, the 15
15 average was 41 milliamperes and the range from 25 to 54 milliamperes. The grid current was less than .1 of a microampere in the magnesium tubes and ranged from .3 to 5.1 microamperes in the zinc tubes.

15 The fact that a zinc clean-up leaves some gas, and, at the same time, cleans up those gases that reduce the electron-emission of filaments containing thorium, makes it advantageous for use in detector tubes. If it is 20 desired to more completely eliminate the gas in the tube, some other material, for example, magnesium may be used in combination with the zinc.

25 Although I have described in detail what are now considered to be the preferred means of practicing my invention, as applied to radio tubes, it is to be understood that my invention is applicable to X-ray

What is claimed is:

1. A vacuum device comprising a bulb exhausted to a moderate degree and containing a galvanized iron electrode adapted to be heated to cause a vaporization of the 40 zinc thereon to effect a clean-up action on the residual gases.

2. A vacuum device comprising an envelope evacuated to a moderate degree and containing a thermionically active cathode 45 containing thorium and a plate composed of galvanized iron to which is attached a small piece of magnesium, said plate being adapted to be heated to vaporize the zinc and magnesium, at least in part, to efficiently 50 remove residual gases in the bulb.

In testimony whereof, I have hereunto subscribed my name this 8th day of January, 1923.

DUNCAN MACRAE.
